DESIGN FOR A METAL BARREL

Ross T. Corey, Richmond, Calif.

Application June 24, 1938, Serial No. 78,039

Term of patent 14 years

To all whom it may concern:

Be it known that I, Ross T. Corey, a citizen of the United States, residing at Richmond, in the county of Contra Costa and State of California, have invented a new, original, and ornamental Design for a Metal Barrel, of which the following is a specification, reference being had to the accompanying drawing, forming a part thereof.

Figure 1 is a top plan view of a metal barrel showing my new design.

Figure 2 is a front elevational view of the barrel.

Figure 3 is a bottom plan view thereof.

Figure 4 is a fragmental vertical sectional view of a portion of the barrel. The plane of section is indicated by the line 4—4 of Figure 1.

Figure 5 is a side elevational view of the barrel.

Figure 6 is a fragmental horizontal sectional view of the barrel showing the outer surface contour of the latter along the line 6—6 of Figure 2.

I claim:

The ornamental design for a metal barrel, substantially as shown.

ROSS T. COREY.
